ALLOYS

John Johnson, Toronto, Ontario, Canada

No Drawing. Application June 6, 1938.
Serial No. 212,135

4 Claims. (Cl. 75—155)

This invention relates to alloys such as described in my prior United States Patent No. 2,014,083 dated Sept. 10, 1935, and comprising silver, copper, cadmium and zinc substantially in the proportion of

	Per cent
Silver	33
Copper	30
Cadmium	35
Zinc	2

This alloy gives excellent results but the amount of silver employed makes the alloy rather expensive. Further, this alloy is not as successful as might be desired in brazing stainless steel to stainless steel or other metals.

My object therefore is to provide an alloy containing a smaller proportion of silver than heretofore used without materially affecting the desirable characteristics of the alloy and increasing its adaptability to the brazing of stainless steel.

I attain my object by decreasing the proportion of silver in the alloy and also the proportion of cadmium, at the same time increasing the proportion of copper and to a small extent the proportion of zinc.

In practice I have used silver, copper, cadmium and zinc within the following range of proportions:

	Per cent
Silver	7½ to 25
Copper	62 to 40
Cadmium	19 to 31
Zinc	9½ to 3

Specific examples of alloys according to my invention which I have tried are as follows:

Example	Silver	Copper	Cadmium	Zinc	Melting point
	Percent	Percent	Percent	Percent	° F.
No. 1	25	40	31	4	1076
No. 2	18	48	31	3	1094
No. 3	15½	48	31	5½	1076
No. 4	12	58	21	9	1149
No. 5	10½	57½	22	10	1124
No. 6	9½	60	19	11½	1150
No. 7	7½	62	21	9½	1150
